UNITED STATES PATENT OFFICE.

WILLIAM B. HEWITT, OF HOLYOKE, MASSACHUSETTS, ASSIGNOR, BY MESNE ASSIGNMENTS, TO WORLINGTON PUMP AND MACHINERY CORPORATION, OF NEW YORK, N. Y., A CORPORATION OF VIRGINIA.

DEEP-WELL PUMP.

1,197,631.

Specification of Letters Patent. Patented Sept. 12, 1916.

Application filed January 31, 1914. Serial No. 815,619.

To all whom it may concern:

Be it known that I, WILLIAM B. HEWITT, a citizen of the United States, residing at Holyoke, county of Hampden, and State of 5 Massachusetts, have invented certain new and useful Improvements in Deep-Well Pumps, fully described and represented in the following specification and the accompanying drawings, forming a part of the 10 same.

This invention relates to that class of pumps used especially for deep well pumping, in which a plurality of reciprocating buckets or plungers act on the liquid successively, the object of the invention being to provide an improved power pump of this class, in which the operating connections for the buckets or plungers shall be simple, strong and durable, and all the working 20 parts kept free from sand or grit carried in suspension by the liquid, the bucket rods shall be kept lubricated and a high volumetric efficiency of the pump be secured.

The invention aims particularly at the 25 production of a satisfactory triple acting power pump securing the above results.

In the accompanying drawings forming a part of this specification, a triple acting deep well pump embodying the invention in 30 its preferred form is shown, and this construction will now be described in detail and the features forming the invention then specifically pointed out in the claims.

In the drawings, Figure 1 is a front view 35 of the pump with the pump head in elevation and the pump well in section, with parts of the bucket rods broken away to show the construction. Fig. 2 is a vertical cross section on the line 2 of Fig. 1. Fig. 40 3 is a detail section of two of the buckets, the bucket rods and the arrangement for lubrication. Fig. 4 is a detail of the bucket rod packing.

Referring to said drawings, the frame 10 45 of the pump head is mounted above the well 11 and carries the crank shaft 12, shown as driven by gear 13 from power shaft 14 and pinion 15. The crank shaft 12 carries three separate cranks for operating the three 50 buckets, these cranks being set 120 degrees apart, and connected to the respective buckets as follows: The middle crank 16 is connected by its crank rod 17 and sliding cross head 18 directly to the bucket rod 19

connected to the bottom bucket 20. Outside 55 the crank 16 are the cranks 21, 21 connected by their crank rods 22, 22 and sliding cross heads 23, 23 to rods 24, 24 and yoke 25 attached to the tubular bucket rod 26 which in turn carries the intermediate bucket 27. 60 Outside the cranks 21 are the cranks 28 connected by their crank rods 29, 29 and sliding cross heads 30, 30 to rods 31, 31 and yoke 32 to which is attached the tubular bucket rod 33 which carries the top bucket 65 34. The rod 33, with the inclosed concentric rods 26 and 19, moves through the discharge head 35 at the top of the drop tube 36 within the well, a suitable stuffing box 37 being provided and the discharge head 70 35 having a delivery pipe 38.

The above construction provides for the balancing of the buckets and also the balancing of the connections from the buckets to the crank shaft so that side thrusts are 75 eliminated, a high mechanical efficiency is secured, and the wear of the working parts considerably reduced. The construction further provides for convenient access to the working parts and withdrawal upward of 80 the well portions of the pump, by the enlargement of the upper portion of the well and opening of this enlarged portion and frame 10 at the front, and by the removability of the front plate forming one of the 85 two front and rear cross heads 58 and 59, this front plate being secured by bolts 60 or otherwise, as desired. This result is aided also by the setting of the crank shaft 12 slightly to the rear of the bucket rods, 90 so as to provide more room at the front of the pump for lifting the working parts from the well, this offsetting at the same time permitting the use of somewhat shorter connecting rods and securing a quicker down-stroke and more uniform and slower up-stroke. The pump as thus far described 95 is that of my Letters Patent No. 1,102,583, dated July 7th, 1914.

The pump brackets 20, 27 and 34 are provided with the usual packing rings 39, 39, 39; but in addition thereto the two upper buckets 27 and 34, as shown in Fig. 3, are provided with internal guides and packing glands carried within the respective couplings 40 and 41. As shown in Fig. 4, the coupling 40 carries internally a centering guide ring 42 in which the rod 19 has its 100 105

bearing; a suitable packing ring 43 is mounted about the guide ring and prevents the passage of water downward from the space between rods 19 and 26 into the chamber between the buckets 20 and 27; and a similar ring 44 is mounted below the guide ring and prevents the upward movement of sand or grit. The guide ring 45, and packing rings 46, 47 mounted within the coupling 41 are of similar construction and function; in this instance the guide ring 45 forming a bearing for the tubular rod 26. One of the couplings of rod 19 is shown in Fig. 3 at 48, located within the tubular rod 26, and 49 shows a similar coupling for rod 26 which is located within tubular rod 33. These couplings sometimes bear upon the rods which inclose them and it is of advantage to have these annular spaces between the rods filled with water or other lubricant. Inlet pipes 50 and 51 communicate with these spaces, as shown in Fig. 3, and the water, oil, or other lubricant may be supplied as desired by hose 52, 53, while the pump is running and the hose then detached and valves 54, 55 closed. The liquid in these spaces is prevented from flowing below the buckets by packing rings 43 and 46 described above. Air relief valves for the annular spaces are provided at 56 and 57.

This construction prevents the grinding action of sand or grit carried in the liquid; the leakage of liquid past the buckets; the loss of vacuum between the buckets; and thus provides not only for a high volumetric efficiency of the pump, but also the maintenance of such efficiency in cases where the pump has to handle liquid containing sand in suspension. It also permits the continuous application of a lubricant to such working parts as are liable to have frictional contact.

What is claimed is:—

1. In a pump, a movable element comprising a bucket having a central bore and a tubular operating rod, a second and independently movable element comprising a second bucket and operating rod, the latter rod inclosed by and concentric to the first movable element, a ring mounted internally

on the first element to form a bearing for the rod of the second element, and a packing joint to prevent leakage past the said bearing ring.

2. In a pump, a movable element comprising a bucket having a central bore and a tubular operating rod, a second and independently movable element comprising a second bucket and operating rod, the latter rod inclosed by and concentric to the first movable element, a ring mounted internally on the first element to form a bearing for the rod of the second element, and a packing joint below the ring to prevent the movement of sand into the bearing. 65

3. In a pump, a movable element comprising a bucket having a central bore and a tubular operating rod, a second and independently movable element comprising a second bucket and operating rod, the latter rod inclosed by and concentric with the first movable element, a ring mounted internally on the first element to form a bearing for the rod of the second element, and a packing joint below the ring to prevent the movement of sand into the bearing, and a packing joint above the ring to prevent the escape of lubricant from the annular space between the rods. 75

4. In a pump, a movable element comprising a bucket having a central bore and a tubular operating rod, a second and independently movable element comprising a second bucket and operating rod, the latter rod inclosed by and concentric to the first movable element, means to supply a lubricant to the annular space between the rods, a ring mounted internally on the tubular operating rod at the bottom of the lubricant space to form a bearing for the rod of the second bucket, and a packing joint to prevent leakage past the bearing ring. 85 90

In testimony whereof, I have hereunto set my hand, in the presence of two subscribing witnesses.

WILLIAM B. HEWITT.
